UNITED STATES PATENT OFFICE

MAX GOLDBERG, OF NEW YORK, N. Y.

MACHINE FOR PROCESSING FIBROUS FILLING MATERIALS

Application filed September 23, 1927, Serial No. 221,516. Renewed October 3, 1929.

The present invention relates to certain improvements in machines for processing fibrous filling materials such as are commonly used for filling mattresses, pillows, comforters, 5 cushions, etc.

The above mentioned filling materials include; cotton, cotton waste, down, feathers, hair, floss, kapok, jute and similar materials.

The above stated processing consists in; 10 beating or fluffing up, cleaning and mixing the said filling materials.

An object of the present invention is to provide a machine which is simple, durable, inexpensive and of compact construction together with certain novel features whereby the nature of the processing may be varied by simple adjustments on the machine.

One of the main objects is to provide a construction whereby a machine of small proportions will have a very large capacity. 20 Heretofore in machines of this type the filling material to be processed is fed radially inwardly along an axial line on the periphery or to one end of the beater drum and the said filling material is carried around on the beater or picker drum only a part of the circumference, the remainder of the said beater or picker drum being inactive in so far as actual picking goes. I propose a construction of 25 beaters or pickers whereby the material is fed into the machine on the axis at one end of the beater drum and from the said entering position travels axially along the drum utilizing the entire circumference of the said beater drum. As one of the objects I contemplate a construction whereby long fibrous material 30 will not wind up around the main shaft.

Heretofore machines for cleaning hair have been provided with a separate blower for 40 drawing or sucking out dust and a certain amount of the short or broken fibers. In my present invention I contemplate a construction whereby a machine provided with only one blower can be used for hair as well as any 45 of the other materials ordinarily used in this line, to this end I provide a system of ducts and gates which can be regulated to effect more or less cleaning effect for hair, and to provide a method of processing suited to the 50 material.

I further contemplate novel means of eliminating the fire hazard of prior machines.

It will, however, be understood that; I do not limit myself to the exact structural details shown on the drawings and herein described, omissions and additions may be made to suit materials and varying operating conditions and different desired results, details may be modified and varied from that shown without departing from the spirit of the invention. Slight and unimportant details have been omitted for the sake of clarity.

Referring to the drawings—

Figure 1 is a side elevation of a machine constructed according to the present invention.

Fig. 2 is a central vertical longitudinal section of the machine shown in Fig. 1.

Fig. 3 is an end elevation of the machine.

Fig. 4 is a transverse vertical section on the line 4—4 of Fig. 2.

Fig. 5 is a transverse sectional elevation, the section being taken on the line 5—5 of Fig. 2.

Fig. 6 is a transverse sectional elevation, the section being taken on the line 6—6 of Fig. 2.

Fig. 7 is a modified construction of the picker or beater elements that I may elect to use for certain conditions of operations.

Figs. 8, 9 and 10 and 10^a respectively show modified constructions of the picker elements that I may elect to use as a part of the present invention.

Fig. 11 is a central vertical longitudinal section of a machine partly in elevation embodying the present invention in modified form.

Fig. 12 is a transverse section of a modified form of blower unit constructed as a part of the present invention.

Fig. 13 is a section on the line 13—13 in Fig. 12.

Referring now more particularly to Figs. 1, 2, 3 and 4 of the drawings, it will be apparent that in the illustrated embodiment the machine includes side frames 10 and 11, and tie frames 12, 13 and 14 which connect the side frames 10 and 11 together. The said frames 10 to 14 inclusive constitute the main supporting structure of the machine. The 100

main operating elements are carried on a shaft 15 which is supported between the side frames 10 and 11 for rotation by suitable bearings 16 and 17, which may be of the anti-friction type, as shown. The bearing 16 is supported on the tie frame 13, and the bearing 17 is supported from portions of the side frames 10 and 11. Keyed to the shaft 15 at one end of the machine is a material diffuser 18 preferably of conical construction. The diffuser 18 has suitable radial blades, teeth or serrations 19 for a purpose to appear. Adjacent the diffuser 18 and rigidly fixed to the shaft 15 is an initial picker unit or stage 20.

The initial picker unit or stage is composed of a number of rotor sections 21 each of which has radial picker members 22, and stator sections 23 each of which has picker members 24. Each stator section 23 is of annular construction and consists of segments which are rigidly supported from the side frames 10 and 11. The stator sections 23 surround the rotor sections 21. In the rotation of the rotor sections 21, the picker members 22 thereof cooperate with the picker members 24 of the stator sections 23. The active ends of the picker members 22 and 24 are in overlapping relationship so as to set up a thorough processing or picking action. The object in dividing the picker stage into sections is to provide convenient means for increasing or diminishing the picking effect.

Arranged adjacent the initial picker stage 20 is a pusher or expeller 25. The pusher or expeller 25 consists of a disk 26 which is fixedly secured to the shaft 15, and said disk 26 has a series of radially disposed pusher or expeller members or blades 27. An annular shell or drum 28 surrounds the shaft 15 and bearing 17, adjacent the pusher or expeller 25. Surrounding the shell or drum 28 is a shell or drum 29 which is of sufficient length to include within the same a pusher or expeller 25. The walls of the drums 28 and 29 form an annular passage 30. The drum 29 in the end thereof adjacent the pusher or expeller 25 is provided with a multiplicity of perforations 31.

Two or more picker units, or stages may be employed according to the material being processed. In the present instance in addition to the picker or beater stage 20, there is a secondary picker unit, or stage 32 which consists of rotor sections 33 each having radial picker members 34, and a stator section 35 having radially disposed picker members 36. The sections 33 are fixedly secured to the shaft 15 to rotate therewith, and the section 35 is fixedly secured to portions of the side frames 10 and 11. Any preferred number of rotor and stator sections 33 and 35 respectively may be employed.

A casing 37 is constructed to completely inclose the picker units, or stages 20 and 32, and the drums 28 and 29, and said casing has

a hopper 38 at one end which communicates with an inlet 39 adjacent the diffuser 18. The casing 37 also forms a chamber 40 at the rear end of the picker stage 32. A plate 41 is arranged between the side walls 42 of the casing and is supported for sliding movement on angle irons 43 respectively secured to the side walls 42. The opposite ends of the plate 41 cooperate respectively with the walls 44 and 45 of the casing. The plate 41 serves as a valve member and is manipulated by a rod 46 attached as at 47 at one end to the plate 41, and the opposite end thereof has a handle 48. The rod 46 is guided for reciprocation in a guide 49 carried by the frame 14. When the plate 41 is in the position shown in full lines in Fig. 2 the chamber 40 will be closed at the bottom, and a suction passage 50 will be formed adjacent the wall 45. When the position of the plate 41 is reversed, the passage 50 will be closed, and a suction passage 51 will be formed in the bottom of the chamber 40. The casing 37 also forms a chamber or outlet passage 52 with which the passages 50 and 51 may be made to communicate selectively by manipulating the plate 41, and said chamber 52 opens as at 53 to a blower drum 54 held in place by the side frames 10 and 11 and the tie frame 13. Arranged in the drum 54 is a fan 55, the hub 56 of which is keyed as at 57 to the shaft 15 so that the fan 55 will rotate therewith, but slideable thereon. A collar 58 is secured to the shaft 15, and passing through the collar 58 is a pin 59 adapted to be moved into and out of a hole 60 in the hub 56. This provision is made so that the fan 55 may be disconnected. The drum 54 has an outlet 61. When the fan 55 rotates it serves to blow material out through the outlet 61 and also serves to set up a suction action in the passages 30 and 40, passages 50 and 51 when formed, and chamber 52.

In order to convey material to the hopper 38 there is provided an endless conveyor 62 of any preferred construction and which may be juxtaposed with respect to the hopper 38 in any preferred manner. In the present instance the conveyor 62 consists of an endless band 63 which encircles drums or the like 64. The band 63 and drum 64 are arranged in a suitable trough 65 which opens at one end to the hopper 38.

Power is transmitted to the shaft 15 in any suitable manner and in the present instance is driven by a belt 66 and pulley 67 keyed to the shaft 15. The shaft 68 of one of the drums 64 is driven from the main shaft 15 through the intervention of a worm wheel 69 keyed to the shaft 68, a worm 70 in mesh with the worm wheel, said worm being keyed to a shaft 71 journaled in suitable bearings 72 on the side frame 10, and there being pulleys 73 and 74 respectively on the shafts 71 and 15 which are encircled by a belt 75.

When it is desired to process certain materials and particularly for removing short ends, dust and other particles, the material is placed in the conveyor 62 and is fed thereby into the hopper 38 to be subjected to the action of the initial picker stage 20. At this time the valve member 41 will be moved to the position shown in full lines in Fig. 2 in which there will be formed the passage 50 which communicates with the annular passage 30 and the chamber 52. The fan 55 will produce a suction action. The undesirable material such as dust will pass through the perforations 31 from the annular passage 30, through the passage 50, chamber 52, through the opening 53 into the drum 54, and from the drum out through the outlet 61. When processing cotton and similar materials requiring the full picking effect of the machine, the plate or valve member 41 is moved to the position indicated in dotted lines in Fig. 2, thereby closing the suction passage 50 previously formed, and producing the passage 51 at the bottom of the chamber 40. At this time the doors 29' and 37' are closed. The material then passes through the initial picker stage 20, is acted on by the pusher or expeller 25, is then acted on by the secondary picker stage 32, and is drawn through the chamber 40 into the chamber 52, and from the chamber 52 through the opening 53 into the blower drum 54, and then out through the outlet 61.

It is to be observed that the material to be processed as it is conveyed by the conveyor 62 to the hopper 38 to be fed or guided thereby into the machine through the inlet 39, that the diffuser 18 will serve to spread the material and break up lumps or bunches, and thereby aids to start the material through the machine due to the radial blades, teeth or serrations 19. When, as often happens foreign matter such as stones and pieces of metal, such as parts of bale ties, etc., happen to be in the material, the diffuser throws them into a recess 76 by centrifugal force, and thereby prevents the undesirable particles from passing through and damaging the picker elements or other operating parts. A suitable door 77 will be provided in the casing for the purpose of cleaning out the accumulated matter from the recess 76.

It is also to be observed that the material by being fed from one end of the machine so that the material will move endwise, that the processing action will be quickened and the capacity of the machine greatly increased, and that the movement of the material is suddenly reversed to take an upward circulatory movement from the chamber 40 through the chamber 52 out through the blower drum 54. The abrupt reversal of the flow of material and air causes any remaining heavy objects such as seeds and other comparatively heavy foreign particles to be carried outside of the stream line and to be

thrown into a suitable receptacle such as the receiver 78 in the bottom of the drum 52. The receiver 78 is provided with a suitable sieve or screen 79 to prevent the processed material from falling into the receiver when starting and stopping the machine, or in other words, when the machine is not operating at the proper speed, the blower fan 55 would not produce sufficient suction to sustain the material in the air stream.

It is also to be observed that the pusher or expeller 25 serves to expel the processed material after passing through the initial picker element 20, out through openings controlled by doors 29' and 37' respectively of the drum 29 and casing 37, and serves effectively to expel such material as hair, or other material which is impractical to pass the blower of the machine.

The number of picker rotor sections 21 and stator sections 23, and rotor sections 33 and stator sections 35, may be varied to suit the material processed to obtain the results desired in the finished product. It is also to be understood that the picker members 22, 24, 34 and 36 may be arranged in circumferential rows and overlap radially as shown in Figs. 2, 5, 7, 8, 10 and 11, or said picker members may be arranged in staggered and non-overlapping relationship, as shown in Fig. 9.

In Fig. 7 the picker stage or element consists of rotor sections 21' which form with the diffuser 18' a conical body, and stator sections 23' which form an annular conical body. This arrangement facilitates the movement of the material through the picker element.

If desired, the same effect obtained by the arrangement shown in Fig. 7 by utilizing rotor sections 21'' of different diameters, and stator sections 23'' of different diameters, as illustrated in Fig. 8.

In Fig. 9 the picker members 22' and 24' respectively of the rotor and stator sections of the picker element are arranged in a staggered non-overlapping relationship, and each of said picker members is pointed. If desired the picker members 22' and 24' may be embodied by flat disks with integral teeth, as shown in Fig. 10, and Fig. 10a.

In Fig. 11 is shown a machine having an enlarged chamber 40' which serves for the purpose of holding a sufficient quantity of material to effect a thoroughly mixing of the processed material in its passage through the machine. This is necessary because in processing mixed material the operator takes a suitable amount of each kind of material and feeds the same into the machine separately. The enlarged chamber 40' requires longer travel of the materials insuring proper intermixing while the machine is operating at high speed. In the chamber 40' secured to the shaft 15' are agitating and re-

tarding members 80, which serve advantageously for retarding the flow of and for mixing the various materials.

In Figs. 12 and 13 there has been shown a modified form of blower and suction producing means which may be used advantageously for extracting dust and other foreign particles from the processed material. The drum 54' in which the fan 55' rotates is provided with perforations 81, or a screen in the circumferential wall 82. The wall 82 is arranged between the fan and a circumferential wall 83 of the outer drum 54' to provide a material discharge duct 85, and a refuse duct 86. The refuse duct 86 is provided with a suitable regulating valve member 87 for controlling the air flow and cleaning effect through the same.

It is to be understood that certain parts of the machine will be made of brass or bronze, so that if such parts should be struck violently they will not give off sparks apt to ignite the material passing through the machine. This provision will eliminate the possibility of fire.

It will also be apparent that by having the shaft 15 project beyond the bearing 17, and the bearing 17 enclosed by drum 28 and expeller disk 26, the material will not be ignited by heat of the bearing 17.

I claim:

1. In a machine for processing filling materials, a picker consisting of a rotor built up of separate disk sections each having picker members, and a stator built up of separate ring sections each having picker members, the picker members of the rotor sections cooperating with the picker members of the stator sections to set up a picking or mixing action.

2. In a machine for processing filling materials, a picker consisting of a rotor built up of separate disk sections each having picker members, and a stator built up of separate ring sections each having picker members, the picker members of the rotor sections cooperating with the picker members of the stator sections to set up a picking or mixing action, the active ends of the picker members of the rotor sections overlapping the active ends of the picker members of the stator sections.

3. In a machine for processing filling materials, a casing forming an annular passage, stationary and relatively movable cooperating picker members arranged in said passage, means for operating the movable picker members, said picker members arranged in stationary and movable groups, means for feeding material to be processed to said annular passage at one end thereof to be acted on by said picker members, and an expeller operating in said annular passage between said groups of picker members for discharging material from said annular passage.

4. In a machine for processing filling materials, a casing forming an annular passage, stationary and relatively movable cooperating picker members arranged in said passage, means for operating the movable picker members, said picker members arranged in stationary and movable groups, means for feeding material to be processed to said annular passage at one end thereof to be acted on by said picker members, an expeller operating in said annular passage for discharging material therefrom, and means acting on the processed material to discharge it from the machine.

5. In a machine for processing filling materials, a casing forming an annular passage, stationary and relatively movable cooperating picker members arranged in said passage, means for operating the movable picker members, said picker members arranged in stationary and movable groups, means for feeding material to be processed to said annular passage at one end thereof to be acted on by said picker members, an expeller operating in said annular passage for discharging material therefrom, and a suction producing means in communication with said annular passage at the end opposite to that to which the material is fed to cause the material to flow out of the machine.

6. In a machine for processing filling materials, a casing forming an annular passage, stationary and relatively movable cooperating picker members arranged in said passage, means for operating the movable picker members, said picker members arranged in stationary and movable groups, means for feeding material to be processed to said annular passage at one end thereof to be acted on by said picker members, a suction producing means in communication with said annular passage at the end opposite to that to which the material is fed to cause the material to flow out of the machine, and means operative to cause the material to flow through one group of picker members only and out through the machine from a point intermediate the groups of picker members when said suction producing means is stopped.

7. In a machine for processing filling materials, a casing forming an annular passage, stationary and relatively movable cooperating picker members arranged in said passage, means for operating the movable picker members, said picker members arranged in stationary and movable groups, means for feeding material to be processed to said annular passage at one end thereof to be acted on by said picker members, a suction producing means in communication with said annular passage at the end opposite to that to which the material is fed to cause the material to flow out of the machine, and means operative to optionally cause the air stream and the material to flow through each group of picker

members or one group of picker members only.

8. In a machine for processing filling materials, a casing having an annular passage and an outlet passage, first and second picker stages in said annular passage, means connected with said outlet passage for the purpose of inducing a suction action to cause the material to flow out of the machine through said outlet passage, and means operative to optionally cause the material to pass from said annular passage through said outlet passage, after being acted upon by the first picker stage only, or to cause the material to pass from said annular passage through said outlet passage, after being acted upon by the first and second picker stages.

9. In a machine for processing filling materials, a casing having an inlet hopper for the purpose of feeding the material into the machine, and a deflector or breaker mounted for rotation at the throat of the hopper, for the purpose of removing heavy foreign substances and other matter from the material before it enters the machine.

10. In a machine for processing filling materials, a casing having an inlet hopper for the purpose of feeding the material into the machine, a deflector or breaker mounted for rotation at the throat of the hopper, for the purpose of removing heavy foreign substances and other matter from the material before it enters the machine, and a receptacle for said foreign substances and other matter within the casing below said throat.

11. A machine for processing filling materials comprising the combination of a casing having an annular passage, picking means operable in said passage to subject the material passing through said passage to a picking action, a pusher operable in said passage beyond said picking means, a perforated enclosure or screen surrounding said picking means and said pusher for the purpose of extracting dust from the material, said casing and said enclosure or screen having aligned outlet openings adjacent said pusher, and closure members controlling said openings respectively, said pusher serving to discharge the material leaving said picking means through said openings when said closure members are open.

12. A machine for processing filling materials including the combination of a cylindrical perforated enclosure or screen which forms a passage for the materials, picking means operable in said passage to subject the material passing through said passage to a picking action, an expeller operable in said passage, said enclosure having an outlet opening, a closure member controlling said opening, said expeller serving to discharge the material leaving said picking means through said outlet opening when said closure member is open, and suction means cooperating

with said perforated enclosure or screen to remove dust from the material.

13. In a machine for processing filling materials, a casing having an annular passage, stationary and relatively movable cooperating picker units arranged in said passage, means for operating said movable picker units, means for guiding material to be processed to said annular passage at one end thereof to be acted on by said picker units, a pusher having radial blades operating in said annular passage, a screen surrounding said pusher for the purpose of separating dust from the material passing through said picker units, said screen and casing having outlet openings in register adjacent said pusher, and closure members controlling said openings respectively, said pusher serving to discharge the material leaving said picker units through said openings when said closure members are open.

14. In a machine for processing filling materials, a casing having an annular passage, stationary and relatively movable cooperating picker units arranged in said annular passage, means for operating the movable picker units, means for guiding material to be processed to said annular passage to be acted on by said picker units, a suction fan adapted to act on the processed material to discharge it from the machine, a perforated enclosure or screen between the periphery of said fan for the purpose of extracting dust from the processed material, separate outlets for the processed material and dust, and a regulating valve in the dust outlet.

15. In a machine for processing filling materials, a casing having an annular passage, a rotary shaft extending into said annular space stationary picker units in said annular passage, picker units secured to said shaft and arranged in said annular space in cooperating relation to said stationary picker units, means for guiding material to be processed to said annular passage at one end thereof to be acted on by said picker units, a blower and suction producing means in communication with said annular passage at the end opposite to that to which the material enters said annular passage, a perforated enclosure or screen associated with said suction producing means, for the purpose of extracting dust from the processed material, separate outlets through which the processed material and dust is discharged by said blower and suction producing means, and means in the dust outlet for regulating the discharge of dust.

16. In a machine for processing filling materials, a supporting structure, a casing supported by said structure, said casing having an annular passage, a shaft, bearings on said structure which support said shaft for rotation, one end of said shaft projecting beyond one of said bearings into said annular passage, a picker unit fixed on said projecting

shaft end, and said last mentioned bearing being enclosed by enclosing means within said annular passage.

Signed at New York, in the county of New York and State of New York this 21st day
5 of September, 1927.

MAX GOLDBERG.
